FIG.1

FIG. 2

FIG.3

FIG.4

FIG.5

FIG. 1 is a front view of a steam facial appliance embodying our new design;

FIG. 2 is a top plan view thereof;

FIG. 3 is a side elevational view of the hood of the appliance, the opposite side being identical with the side shown;

FIG. 4 is a rear elevational view of the hood; and,

FIG. 5 is a bottom plan view of the hood.

The broken line representation of the steam generating bowl has been omitted from FIGS. 3, 4 and 5 for convenience of illustration.

The dominant features of our design reside in the portions shown in full lines.

We claim:

The ornamental design for a steam facial appliance, as shown and described.
